U.S. PATENT DOCUMENTS

D274,458 S * 6/1984 Doman D23/305
D277,695 S * 2/1985 Blodee D23/275

FIG. 1 is a perspective view of a bath surround showing my new design;

FIG. 2 is a front elevation view thereof;

FIG. 3 is a top plan view thereof; and,

FIG. 4 is a left side view with the right side being a mirror image thereof.

The broken lines showing of a bath tub is for illustration purposes only and forms no part of the claimed design.
